UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL RECEPTACLE AND ATTACHMENT.

Application filed July 14, 1920. Serial No. 396,198.

My invention relates to electrical devices and more specifically to a wall receptacle or the like, and an attachable fixture for connection therewith.

One of the objects of my invention is to provide such a construction which will be durable and efficient in use, compact in construction and cheap to manufacture.

Further objects will appear from the detailed description to follow and from the appended claims.

In the drawings in which an embodiment of my invention is shown:

Fig. 1 is a face view of a wall receptacle; Fig. 2 is a vertical section through the wall receptacle and a fitting secured thereto;

Fig. 3 is an end view of the connecting end of the fitting shown in Fig. 2;

Fig. 4 is a vertical sectional view showing the connection between the fitting and receptacle;

Fig. 5 is a horizontal section on the line 5—5 of Fig. 2;

Fig. 6 is a face view of the receptacle base and the parts supported thereby;

Fig. 7 is a sectional view showing the switch mechanism;

Fig. 8 is a face view of the receptacle with the fixture removed and a cover substituted; and

Fig. 9 is a perspective view of the cover shown in Fig. 8.

The construction shown in the drawings comprises in a general way a duplex receptacle 10 mounted in a metal outlet box 11, and an electrical fixture or fitting 12 which can be detachably secured with respect to the receptacle 10. The duplex receptacle 10 is shown as having a receptacle portion 13 for cooperation with a connecting device of the push-in type, and a receptacle portion 14 of the Edison type.

The Edison receptacle is of the "safety" type, that is, both the shell and center contacts 15 and 16 respectively, are normally dead, and are not electrically connected with the feed circuit until the connector device is screwed in. This is accomplished by providing the center contact 16 with a quick-break switch mechanism 17, which is moved to "on" position to connect the center contact 16 with the feed circuit when the connector is screwed in, and making the threaded shell contact 15 tilttable so that it may be brought

into and out of contact with respect to the 65 live contact member 18.

Before describing in further detail the construction of the Edison receptacle, I will describe the construction of the fixture 12 and the cooperating receptacle portion 13. In 60 order to electrically connect the fixture 12 with the receptacle 13, the fixture is provided with a pair of push-in contact blades 19, which can be pushed into engagement with a pair of spring contact finger devices 20 secured to the receptacle portion 13. In order to mechanically connect the fixture 12 with the receptacle portion 13, the fixture 12 is provided with a pair of hook members 21 (see Fig. 4) which hook into a pair of openings 22 in the supporting plate 23, which is secured to the outlet box 11 by means of screws 24. As shown in Fig. 4 the shanks of the hooks 21 substantially fill the holes 22 when the fixture is swung down into position, and as the upwardly-extending hook portion 21 extends behind the supporting plate 23 the fixture 12 cannot be disconnected from the receptacle portion 13 by means of a downward or sidewise force exerted on the fixture. 70

As shown in Fig. 4, the hooks 21 are provided with shoulder portions for engagement with the inner and outer faces respectively of the supporting plate 23, to prevent in and out movement of the hooks after they are connected. The upper shoulder of the hook engages the inner face of the plate and the lower shoulder of the hook engages the outer face of the plate. 80

In order to prevent the fixture from being disconnected by an upward force exerted on the fixture, the yoke-shaped latching member 25 is provided (see Figs. 3 and 4) which latching member is slidably mounted on the fixture 12, and has a pair of latching fingers 26 which swing into a pair of openings 27 in the supporting plate 23 when the fixture 12 is swung down about the hooks 21 as a pivot. After the latching fingers 26 have 90 swung into openings 27 the latching member 25 may be pulled up by means of a thumb screw 28, which pulls the latching fingers 26 up to the position shown in Fig. 4, in which the upper edge of the opening 27 is engaged 100 in a notch in the latching finger 26.

The hook members 21 may be formed as integral parts of a sheet metal stamping, this

stamping comprising also a cup-shaped portion 29 which is secured to the stem or conduit 30 of the fixture by means of a bushing 31. The stem or conduit 30 may support any suitable lamp fitting, such as an angle socket or the like. The cup-shaped member 29 serves to enclose the circular insulating base 32 to which the contact blades 19 of the fixture and the corresponding wiring terminals 33 are secured. The blades 19 may be formed as part of an integral stamping, which integral stamping also comprises the binding plate of the binding terminal 33. These stampings forming the binding plates and contact blades are secured to the insulating base by means of hollow rivet members 34 embedded in the insulating base 32 (Fig. 5).

For housing the base of the fixture, a suitable ornamental canopy or cup-shaped housing member 35 is provided, which is slipped on over the stem or conduit 30 and embraces the bushing 31 and the cup-shaped stamping 29 and the parts supported thereby.

The head of the screw 28, previously referred to, bears on this canopy 35 and is threaded into the cross-bar of the yoke-shaped latching member 25 so that screwing in on the screw 28 will draw the latching member 25 upwardly, to cause the latching member 26 to engage the supporting plate 23.

To connect the fixture 12 with the wall receptacle, the outer end of the fixture is tilted up, and the hook members 21 are inserted in the holes 22, and the fixture is then swung down about the hooks 21 as a pivot to cause the latching members 26 to enter the lower openings 27. The screw 28 is then screwed into the latching member 25 to cause the latch fingers 26 to be drawn upwardly, so that the supporting plate 23 will engage within the notches of these latching fingers.

As the fixture 12 is swung down, the projecting contact blades 19 will swing into and enter the openings 36 in the receptacle portion 13 and will engage the spring contact devices 19. This swinging into engagement of the contact blades 19 is feasible because the contact blades are not extremely long and because the lower edges of the openings 36 are elongated somewhat to permit the blades to pass in their swinging movement.

It will be seen that the fixture 12 may thus be firmly supported with respect to the receptacle portion 13, and that the connecting parts will be completely enclosed and housed in the ornamental canopy or housing 35.

For guiding the latching member 25 in its sliding movement, the arm 37 is provided with elongated slots 38, which engages lugs 39, formed integral with the cup-shaped stamping member 29.

Referring now more in detail to the construction of the safety Edison receptacle, the

switch mechanism shown herein comprises a pivoted switch arm 40, oscillatable back and forth, a coil compression spring 41 acting on the oscillatable arm 40, a swinging spring shifting link 42 on which the spring 41 is mounted, a returning spring 43 for returning the spring shifting link 42 after it has been pushed in by the center contact 16, and a switch frame 44 for supporting the various parts of the switch. The switch arm 40 is movable into and out of engagement with respect to a pair of spring contact fingers 45, one of which contact fingers is electrically connected with the wiring terminal 46 (Fig. 6) by means of the conducting strip 47, and the other of which is electrically connected with the center contact 16, which acts on the plunger 48, to actuate the switch mechanism 17. The electrical connection between the spring contact fingers 45 and the center contact 16 is effected by means of the conducting strip 49, and the screw 50, which is threaded into the nut 51 to hold the center contact in place.

For normally holding the threaded shell contact 15 out of engagement with the live contact 18, a U-shaped wire spring 52 is provided, the arms of which straddle the threaded shell contact and bear on the flange portion 53 thereof, to hold this flange portion 53 away from the live contact 18. When, however, the insertable device is screwed into the threaded shell contact 15, and engages the center contact 16, the first effect is to pull the upper edge of the threaded shell contact outward, to bring the flange 53 into engagement with the live contact 18. This movement of the threaded shell contact takes place before the movement of the center contact, because of the relative stiffness of the springs 43 and 52. The spring 43 is so stiff that the center contact will not yield until the threaded shell contact 15 has been pulled out and brought to a stop against the live contact 18. Thereupon a further screwing in of the plug will push the center contact 16 inward and this will act on the plunger 48 to cause the switch mechanism 17 to move to "on" position to connect the center contact 16 electrically with the wiring terminal 46 thus completing the circuit.

As shown in Fig. 6, the live contact 18 is always electrically connected with the wiring terminal 54. Also as shown in Fig. 6 the spring contact devices 20 are electrically connected with the wiring terminals 46 and 54 respectively.

In order to provide a finished appearance to the wall receptacle when the fixture 12 is removed, a detachable sheet metal cover 55 is provided, to which is secured a slip 56 having a pair of notched fingers 57 which may be made to engage the lower edges of the openings 27 in the supporting plate 23.

to hold the ornamental plate 55 in its proper position as shown in Fig. 8.

Having thus described my invention, what I claim as new and desire to secure by Letters Patent of the United States is:

1. The combination with a receptacle having its face lying in a substantially vertical plane, of a plug-in device comprising a plug-in portion and a conductor conduit extending from said plug-in portion and interengaging means on said receptacle and plug-in device, for supporting said plug-in device with its conduit in horizontal position, said interengaging means comprising a hook fixedly secured to said plug-in device, and latching means comprising a yoke-shaped member slidably mounted on said plug-in device, and having a pair of latching fingers on the yoke arms. 10
2. The combination with a receptacle having its face lying in a substantially vertical plane, of a plug-in device comprising a plug-in portion and a conductor conduit extending from said plug-in portion, and means on said receptacle and said plug-in device for supporting said plug-in device with its conductor conduit in horizontal position, said means comprising a cup-shaped housing, a hook secured to said cup-shaped housing and guide fingers also secured to said cup-shaped housing, and latching means comprising a member slidably mounted on said guide fingers, and having a latch finger for engaging said receptacle, said plug-in device comprising an insulating base located in said cup-shaped housing and contact members supported by said insulating base. 20
3. The combination with a receptacle having a vertical face, and an apertured supporting plate adjacent said face, of a combination electrical connector and fixture supporting device, and a fitting supported thereby, said combination device being provided with means including hooks insertable through the apertures in said plate to hook behind said plate whereby it can be connected with respect to said receptacle by means of a downward swinging motion about said hook connection and means for preventing said fitting from being swung upwardly. 30
4. The combination with a receptacle having a vertical face, and an apertured supporting plate adjacent said face, of a combination electrical connector and fixture supporting device, and a fitting supported thereby, said combination device being provided with means including hooks insertable through the apertures in said plate to hook behind said plate whereby it can be connected with respect to said receptacle by means of a downward swinging motion about said hook connection and latching means for preventing said fitting from being swung upwardly. 40
5. The combination with a receptacle having its face substantially vertical, and provided with a supporting plate having a flat apertured portion, of means for electrically connecting the fixture with said receptacle and mechanically connecting and securing said fixture with respect to said receptacle, said means comprising plug-in contacts for engaging the receptacle contacts, and a plurality of hook members having shanks extending through said apertured flat portion and head portions engaging behind said flat portion, one located above said contacts, and one located below said contacts. 50
6. The combination with a receptacle provided with a supporting plate having a flat portion, of means for electrically connecting the fixture with said receptacle and mechanically connecting and securing said fixture with respect to said receptacle, said fixture having a stem, and said means comprising plug-in contacts for engaging receptacle contacts, and a bracket secured to said stem and provided with at least three hook members cooperating with said flat portion, and surrounding said contacts, said plate having apertures through which said hooks may be inserted to hook in behind the plate. 60
7. The combination with a receptacle provided with a supporting plate having a flat portion, of means for electrically connecting the fixture with said receptacle and mechanically connecting and supporting said fixture with respect to said receptacle, said means comprising an insulating base, plug-in contacts mounted on said base for engaging the receptacle contacts, at least three hook members cooperating with said flat portion and surrounding said plug-in contacts, and provisions for relative sliding movement between a number of said hooks and said insulating base, said plate having apertures through which said hooks may be inserted to hook in behind the plate. 70
8. The combination with a receptacle provided with a supporting plate having a flat portion, of means for electrically connecting the fixture with said receptacle and mechanically connecting and supporting said fixture with respect to said receptacle, said means comprising an insulating base, plug-in contacts mounted on said base for engaging the receptacle contacts, at least three hook members cooperating with said flat portion and surrounding said plug-in contacts, and provisions for relative movement between a number of said hooks and said insulating base, said plate having apertures through which said hooks may be inserted to hook in behind the plate. 80
9. The combination with a receptacle having its face substantially vertical, and provided with a supporting plate having a flat apertured portion, of means for electrically connecting the fixture with said receptacle and

mechanically connecting and securing said fixture with respect to said receptacle, said means comprising plug-in contacts for engaging the receptacle contacts, and a plurality of hook members extending through said apertured flat portion and surrounding said contacts, some located above and some located below said contacts, said hook members having points extending in the same direction and engaging behind said flat portion.

10. The combination with a receptacle provided with a supporting plate having a flat portion, of means for electrically connecting the fixture with said receptacle and mechanically connecting and supporting said fixture with respect to said receptacle, said means comprising plug-in contacts for engaging said receptacle contacts, a plurality of hook members having hooked engagement with said supporting plate, and latching means for holding said hook members in hooked engagement with said plate said plate having apertures through which said hooks may be inserted to hook in behind the plate.

11. The combination with a receptacle provided with a supporting plate having a flat portion, of means for electrically connecting the fixture with said receptacle and mechanically connecting and supporting said fixture with respect to said receptacle, said means comprising plug-in contacts for engaging said receptacle contacts, a vertical supporting plate, a plurality of hook members having hooked engagement with said supporting plate, and latching means engaging said plate for holding said hook members in hooked engagement with said plate said plate having apertures through which said hooks may be inserted to hook in behind the plate.

12. The combination with a receptacle provided with a supporting plate having a flat portion, of means for electrically connecting the fixture with said receptacle and mechanically connecting and supporting said fixture with respect to said receptacle, said means comprising plug-in contacts for engaging the receptacle contacts, a plurality of hook members cooperating with said flat portion, a canopy for housing said means, and means accessible from the outside of said canopy for holding said hook members in hooked engagement with said plate said plate having apertures through which said hooks may be inserted to hook in behind the plate.

13. The combination with a fixture and a receptacle, of means for electrically connecting said fixture with respect to said receptacle and mechanically connecting and supporting said fixture with respect to said receptacle, said means comprising a supporting plate having a flat portion, a plug-in device having plug-in contacts for engagement with contacts of the receptacle, and a bracket on which said fixture is mounted, said bracket

being provided with hook members, and said flat portion being apertured to afford passages therethrough to enable the hook members to be inserted and hooked behind said plate, and to provide for the engagement of said plug-in device with said receptacle.

14. The combination with a fixture and a receptacle, of means for electrically connecting said fixture with respect to said receptacle, and mechanically connecting and supporting said fixture with respect to said receptacle, said means comprising a supporting plate having a flat portion, having openings therein, said plug-in device having plug-in contacts for engagement with contacts of the receptacle, and a plurality of hook members for extending through the openings in said supporting plate, each of said hook members being provided with a pair of shoulders, for engaging the inner and outer faces of said plate respectively, to prevent in and out movement of said hook with respect to said plate.

15. An outlet box, a flat plate in front of said outlet box, a receptacle carried by said plate, said receptacle being provided with spaced entrance openings to receive the contact blades of a separable attachment plug cap, said plate having an opening into which said receptacle projects substantially flush with said plate, and having a plurality of holes surrounding said opening and distinct therefrom, means for electrically connecting a fixture with said receptacle, and mechanically connecting and supporting it with respect thereto, comprising a plug-in device having contact blades for engagement with said receptacle contacts, and a bracket having a plurality of hook members positioned to enter said holes to connect said bracket with said plate.

16. An outlet box, a flat plate in front of said outlet box, a receptacle carried by said plate, said receptacle being provided with spaced entrance openings to receive the contact blades of a separable attachment plug cap, said plate having an opening into which said receptacle projects substantially flush with said plate, and having a plurality of holes surrounding said opening and distinct therefrom, means for electrically connecting a fixture with said receptacle, and mechanically connecting and supporting it with respect thereto, comprising a plug-in device having contact blades for engagement with said receptacle contacts, and a bracket having a plurality of hook members positioned to enter said holes to connect said bracket with said plate, and locking means for holding said hook members in said holes.

17. The combination of a supporting plate adapted to be secured over an outlet box, a receptacle secured to one side of said plate, said plate having an opening and said receptacle having a portion extending through

said opening, and provided with recesses, electrical contacts in said recesses, and a combined fixture supporting and electrical connecting device, comprising a base of insulating material, contacts carried thereby arranged to enter said recesses and engage with the electrical contacts, and a member having a plurality of hooks, said supporting plate having holes for receiving said hooks, said base having sliding movement relatively to said member to permit the connection of said member with said plate by thrusting the hooks into said holes and moving said hooks and said member parallel with said plate.

18. The combination of a supporting plate adapted to be secured over an outlet box, said plate having an opening, a receptacle carried thereby, and having a portion accessible through said opening, and substantially flush with said plate, said plate having a plurality of holes spaced away from said opening, said receptacle having recesses, electrical contacts in said recesses, and a fixture securing and electrical connecting device, comprising a member having hooks for entering said holes and a base having contacts for engaging the receptacle contacts, said base and hook-carrying member having relative movement to permit the hooks to be inserted into said holes and said member to be moved parallel with the face of said receptacle to cause said hooks to engage behind said plate.

19. A combined fixture support and electrical connector, comprising a plate having side flange portions extending at right angles with said plate, and having a pair of hooks formed thereon for insertion into holes in a supporting plate, an insulating base located between said flange portions and electrical connecting blades carried by said insulating base for insertion into a receptacle.

20. A combined fixture support and electrical connector for cooperation with a receptacle provided with an apertured supporting plate, comprising an insulating base, electrical contacts carried by said base for insertion into the receptacle, a plurality of hooks for insertion into apertures in said supporting plate, and means for slidably mounting said hooks with respect to said base, whereby said hooks can be moved into engaging position with the plate after the plug contacts have been inserted into the receptacle.

21. In a lighting fixture, a wall portion comprising a receptacle having contacts and a flat face plate having a flat front, said flat front being provided with a plurality of spaced openings, and a hanging portion comprising a member having hooks for engagement with the edges of the face plate openings and a plug having contacts, said

member and plug being movable relatively to each other whereby the member may be moved to bring the hooks into engagement with the edges of the face plate openings after the plug contacts have been engaged with the receptacle contacts.

22. In combination, a plug receptacle having contacts, a flat face plate in front of the receptacle and having a central opening affording access to said receptacle and a plurality of additional openings adjacent said central opening, means for mechanically securing a fixture in position with respect to said receptacle comprising a member having hooks which engage with the edges of said additional openings, means for electrically connecting said fixture with respect to said receptacle comprising a plug having contacts for engaging the receptacle contacts, said plug and member being movable relatively to each other whereby said hooks may be brought into engaging position with the face plate after the plug contacts have been engaged with the receptacle contacts, and means for locking the hanging portion of the fixture to the wall portion.

23. In a lighting fixture, a wall portion comprising a receptacle having contacts and a face plate having a flat front provided with slots, and a member having hooks adapted to enter said face plate slots and be moved into engagement with the edges of said slots, and a plug embraced by said member having contacts adapted to be pushed into engagement with the receptacle contacts at the same time the hooks enter the face plate slots, said member being movable relatively to the plug to bring the hooks into engagement with the edges of the face plate slots.

24. In a lighting fixture, a wall portion comprising a receptacle having contacts and a face plate having a flat front provided with slots, and a member having hooks adapted to enter said face plate slots and be moved into engagement with the edges of said slots, a plug embraced by said member having contacts adapted to be pushed into engagement with the receptacle contacts at the same time the hooks enter the face plate slots, said member being movable relatively to the plug to bring the hooks into engagement with the edges of the face plate slots, and means for locking the member to the face plate.

25. A fixture unit comprising a securing member having side portions, spaced hook members formed integral with and projecting forwardly from the marginal edges of said side portions and a contact plug mounted between said side portions and having a limited amount of movement relative to the securing member.

26. The combination, a plug receptacle, a supporting plate having a flat apertured por-

tion, and fixture means comprising a securing part having a plurality of retaining projections and a plug loosely mounted with respect to said part so that the part may be moved relatively to the plug, said plug being adapted to make electrical connection with the plug receptacle and said projections being adapted to pass through the apertured plate and by movement of the part which carries the projections relatively to the plug and the face plate, bring such projections into locking engagement with the face plate.

27. The combination, a plug receptacle, a supporting plate having a flat apertured portion, and fixture means comprising a securing part having a plurality of retaining projections and a plug loosely mounted with respect to said part so that the part may be moved relatively to the plug, said plug being adapted to make electrical connection with the plug receptacle and said projections being adapted to pass through the apertured plate and by movement of the part which carries the projections relatively to the plug and the face plate bring such projections into locking engagement with the face plate and means for locking the securing part with respect to the face plate.

28. In combination, a plug receptacle having contacts, a face plate having a flat apertured portion, a fixture, and means for mechanically securing and electrically connecting the fixture with respect to said receptacle, comprising a member having supporting projections adapted to pass through and engage behind the apertured plate, and a plug movably mounted with respect to said member and having contacts for co-operation with the receptacle contacts. 35 40

29. The combination of a supporting plate adapted to be secured over an outlet box and having an opening and a plurality of holes surrounding said opening and distinct therefrom, a receptacle carried by the plate projecting into said opening substantially flush with said plate, and means for electrically connecting a fixture with said receptacle and mechanically connecting and securing a fixture with respect to said receptacle, comprising a plug-in device having plug-in contacts for engagement with the receptacle contacts, and a bracket having a plurality of hook members positioned to enter said holes. 45 50 55

In witness whereof, I have hereunto subscribed my name.

REUBEN B. BENJAMIN.
